UNITED STATES PATENT OFFICE.

OLIVER C. GILBERT, OF NEW YORK, N. Y.

METHOD OF DETERMINING TEMPERATURES IN METAL-WORKING.

1,379,909.

Specification of Letters Patent. Patented May 31, 1921.

Application filed June 21, 1919. Serial No. 305,756.

To all whom it may concern:

- Be it known that I, OLIVER C. GILBERT, a citizen of the United States, residing at New York, in the county of New York, 5 State of New York, have invented certain new and useful Improvements in Methods of Determining Temperatures in Metal-Working, of which the following is a full, clear, concise, and exact description.
- 10 This invention relates to a method of determining the temperature to which metals and their alloys are heated in passing through a die.
- 15 The drawing of metals and their alloys through a die, due to the friction between the metal and die as well as fluid friction within the metal during the reduction, heats both metal and die to a high temperature, the degree thereof depending upon the
- 20 amount of reduction, the hardness of the metal, and the speed at which the metal passes through the die as well as upon the condition of the die itself. In the commercial drawing of metals it is desirable to attain 25 the greatest speed possible in a given reduction without injuring the metal. To permit of high speed in drawing the metal through the die, in practice, a lubricant is applied to the metal and die to lower the
- 30 temperature of both sufficiently to prevent injury to the metal and at times the operation is conducted under water to offset heating. Where a lubricant is used efficiently, only enough is employed to keep the metal and die at the desired temperature. Heretofore, 35 the temperature of the lubricant necessary in any given reduction process has been determined by continued experiment both in the application of lubricants of different temperatures and also in the speed of reduction. Such a method is slow and also expensive, since the metal that is annealed or over-drawn must be discarded but has been necessary due to the difficulty of ascertaining the effect of the drawing during the reduction process.
- 40 Metal that has been drawn through a die has a dissimilar physical state from the undrawn metal, the molecules of the former being dissimilarly oriented, whereby it possesses greater tensile strength. Since the drawn and undrawn metals are dissimilar in physical characteristics and since at the point of reduction, or in other words, with-

55 in the die, heat of high temperature is generated due to the reduction, a thermo-couple is formed between the drawn and undrawn metal.

The present improved method contemplates the use of this thermo-couple in the usual manner by applying the brushes of a delicate galvanometer to the metal just before and after it leaves the die, as is illustrated in the accompanying drawing, Figures 1 and 2 thereof being diagrammatic illustrations showing the several steps of the method, 1 representing the galvanometer, the brushes 2 and 3 of which are applied to the metal just before and after it leaves the die 4. During the reduction of the metal, 60 the thermopile previously described will generate a thermo-electromotive force or current which will be measured or indicated on the galvanometer. When the desired speed of reduction has been reached the 65 reading of the galvanometer is noted and the reduction of the metal is stopped. The section of the metal extending from a point beyond the brush 2 to a point beyond the brush 3, as indicated by the dotted lines 5, 70 is then cut from the body of the metal and withdrawn from the die. This section of metal is bent into a U-shape and then immersed in a tank 6 containing oil, the ends of the metal, however, protruding beyond 75 the oil and with the brushes 2 and 3 of the galvanometer attached thereto at the same points as they occupied during the reduction. The oil in the tank is then heated by a Bunsen burner, or other suitable means, 80 until the galvanometer registers the same reading as the one previously noted. In this instance the thermo-electromotive force is generated due to the same dissimilar physical characteristics in the section of metal, 85 the heat of the oil serving in lieu of the heat caused by the friction of the die. A thermometer 8 immersed in the oil bath during the heating of the oil will indicate the temperature of the metal for the given 90 galvanometer reading. In this manner a galvanometer may be calibrated for any given metal.

95 Knowing the temperatures indicated by the various readings of the galvanometer for a given metal, any desired temperature of the metal during reduction may be had by applying a refrigerant and regulating the

speed of reduction until the desired temperature is indicated by its corresponding reading on the galvanometer.

What is claimed is:

- 5 1. The method of determining the temperature of a metal or alloy as it passes through a die, which involves a measurement dependent upon a movement of the metal or alloy and proportional to the electromotive force developed by the thermo-couple formed by the drawn and undrawn metal or alloy while it is passing through the die.
- 10 2. The method of determining the temperature of a metal or alloy as it passes through a die, consisting in measuring the thermo-electromotive force generated by the passage of the metal or alloy through the die in a given reduction, heating the metal or alloy after it has been partly passed through the die in a fluid until the same measured thermo-electromotive force is attained, and simultaneously measuring the temperature of the said fluid.
- 15 3. The method of determining the temperature of a metal or alloy as it passes through a die, consisting in measuring the electrical effect produced by the thermo-couple formed by the drawn and undrawn metal or alloy and comparing this effect with that produced by the same couple at known temperatures.
- 20 4. The method of determining the temperature of a metal or alloy as it passes through a die consisting in applying the brushes of a galvanometer to the metal or alloy just before and just after it leaves the die, noting the reading of the galvanometer for any given reduction, cutting from the body of the metal or alloy a section comprising a drawn portion and an undrawn portion, bending the section into a U-shape and immersing it in a fluid with portions projecting beyond the same, applying the brushes of the galvanometer to the projecting portions of the metal or alloy, heating the fluid until the previously noted reading of the galvanometer is attained, and simultaneously measuring the temperature of the said fluid.

until the previously noted reading of the galvanometer is attained, and immersing a thermometer in the fluid to measure the temperature thereof.

5. The method of determining the temperature of a metal or alloy as it passes through a die consisting in applying the brushes of a galvanometer to the metal or alloy just before and just after it leaves the die, noting the reading of the galvanometer for any given reduction, cutting from the body of the metal or alloy a section which comprises a drawn portion and an undrawn portion, immersing the section of metal or alloy in a fluid with portions projecting without the same, attaching the galvanometer brushes to the projecting portions of the metal or alloy, heating the fluid until the previously noted reading of the galvanometer is attained, and immersing a thermometer in the fluid to measure the temperature thereof.

6. The method of determining the temperature of a metal or alloy as it passes through a die consisting in applying the brushes of a galvanometer to the metal or alloy just before and just after it leaves the die, noting the reading of the galvanometer for any given reduction, cutting from the body of the metal or alloy a section comprising a drawn portion and an undrawn portion, bending the section into a U-shape and immersing it in a fluid with portions projecting beyond the same, applying the brushes of the galvanometer to the projecting portions of the metal or alloy, heating the fluid until the previously noted reading of the galvanometer is attained, and simultaneously measuring the temperature of the said fluid.

In witness whereof, I hereunto subscribe my name this 19th day of June A. D., 1919.

OLIVER C. GILBERT.
